CONTROL MECHANISM FOR CONCRETE-MIXING APPARATUS

Application filed March 11, 1929. Serial No. 345,949.

The present invention relates to a concrete mixer and more particularly to a control device operatively associated with the mixer for locking the discharge chute in non-discharging position upon charging of a batch of ingredients into the mixing drum, and for permitting lowering of said chute to discharging position only after a predetermined number of revolutions have been made by the 10 mixing drum following such charging operation.

Heretofore, the ingredients directed into the drum were revolved until they were considered to be sufficiently mixed, which was 15 determined by mere visual inspection. In accordance with this method the concrete produced frequently did not satisfy the required tests, for, if the mixing period was too short, the concrete would contain an excess of cement in some portions and an inadequate supply of cement in other portions. On the other hand, if the time of the mixing period was above the time normally required, considerable labor would be wasted in waiting 20 for the supply of wet concrete, and the full efficiency of the equipment would not be realized.

Accordingly, it is an object of our invention to provide improved means for accurately controlling the duration of the mixing operation of the ingredients, such as rock, sand, cement and water, so as to produce concrete which will possess the desired qualities and characteristics, namely, uniform 25 strength, durability, consistency, and to give maximum efficiency of utilization of labor and equipment.

Another object of the invention is to provide novel releasing means for permitting 30 discharge of the wet concrete from the drum or mixer after the ingredients have been mixed to the predetermined extent, or after the mixer has made a predetermined number of revolutions.

More particularly, an object of the invention is to provide means for controlling the mixing operation by prevention of the lowering 35 of the discharge chute until the mixer has made a predetermined number of revolutions, and for locking the discharge chute

in inoperative position until a predetermined mixing action has been given to the ingredients in the mixing drum.

Still another object of our invention is to employ and utilize the charging hopper to 45 actuate or re-set the control mechanism, whereby the mixing operation will continue for a predetermined number of revolutions after charging and preparatory to the discharge of the concrete from the drum or 55 mixer.

Another object of our invention is in the provision of means for starting the control mechanism during the first revolution of the 60 drum after charging the ingredients into said drum, and in the provision of improved means whereby the discharge chute may be raised at any time after the hopper has directed the ingredients into the drum even though the control mechanism has already 65 started operating.

A further object of the invention is the provision of a control device which may be made and sold as a separate unit, and which 70 may be mounted upon, and used in connection with, any type of rotating concrete mixer.

A further object of the invention is to provide a control mechanism offering a simple 75 means for varying the duration of the mixing 80 operation as desired.

Specifically, the invention comprehends the use of novel means for locking the discharge chute in inoperative position whereby the control mechanism actuated by the rotation of the drum will release the chute locking means after a predetermined number of revolutions of the drum.

Another aspect of our invention is to provide an audible signal to notify the operator 85 that the drum has made a predetermined number of revolutions and that the chute locking means has been released to permit lowering of the chute to the delivery position.

More particularly the invention contemplates the utilization of novel means for actuating a control member or rack whereby the latter may be advanced in travel upon each 90 revolution of the drum and held in the ad- 100

vanced position by an improved holding means.

It is to be understood that the apparatus herein disclosed is merely suggestive of a type of apparatus that may be employed in carrying out the new method of operation, it being understood that any other suitable apparatus may be employed within the spirit and scope of the invention.

10 The invention is exemplified in the combination and arrangement of parts shown in the accompanying drawings and described in the following specifications, and it is more particularly pointed out in the appended claims.

15 Referring to the drawings:—

Fig. 1 is a side view of the mixing drum mounted on a portable carriage illustrating the feed hopper and discharge chute in lowered and raised positions by full and broken lines respectively.

Fig. 2 is a perspective and enlarged broken view of a portion of the mechanism shown in Fig. 1.

20 Fig. 3 is a plan view of the control mechanism with the top plate removed.

Fig. 4 is a fragmentary plan view of a part of the control mechanism.

Fig. 5 is a sectional view taken on the line 30 5—5 in Fig. 3 in the direction of the arrows, illustrating the compound lever in normal or elevated position.

Fig. 6 is a sectional view taken on the line 35 6—6 in Fig. 3 in the direction of the arrows illustrating in full lines the compound lever depressed by the re-setting rod and the dotted lines indicating the lever in normal position, after the complete forward stroke of the re-setting rod.

40 Fig. 7 is a fragmentary view taken on the line 7—7 in Fig. 3, in the direction of the arrows, with the control member at or near the outer end of its movement.

Fig. 8 is a longitudinal broken sectional view taken on the line 8—8 in Fig. 3 in the direction of the arrows, but with the control member in an intermediate position.

Fig. 9 is a view in perspective of the end portion of the actuating lever, shown in 50 Figs. 2 and 5.

Fig. 10 is a perspective view of one end of the re-setting rod.

Fig. 11 is a view in perspective of the compound lever.

55 Fig. 12 is a plan view of the locking bar.

Fig. 13 is a view in perspective of the locking bar showing the latch member thereof, but in section, taken on the line 13—13 of Fig. 12 looking in the direction of the arrows.

60 Fig. 14 is a diagrammatic side elevation of a modification.

Fig. 15 is a broken plan view of the timing apparatus of Fig. 14 with the top plate removed.

65 Fig. 16 is a sectional view taken on line

16—16 of Fig. 15 in the direction of the arrows, but with pinion moved to inoperative position.

Fig. 17 is a longitudinal sectional view taken on the line 17—17 in Fig. 15 in the direction of the arrows.

Fig. 18 is a sectional view on the line 18—18 in Fig. 15 looking in the direction of the arrows.

Fig. 19 is a fragmentary sectional view on the line 19—19 in Fig. 17 looking in the direction of the arrows.

In accordance with the preferred embodiment, it is proposed to re-set the control mechanism, that is, to return the same to a starting position, by the charging hopper as the ingredients are fed into the drum, and to automatically sound an audible alarm signal after the drum has made a predetermined number of revolutions, notifying the operator that the chute has been unlocked by the control mechanism and that the chute may be manually lowered for discharging the mixed concrete from the drum.

Referring to the embodiment illustrated in Figs. 1 to 13 inclusive, 10 denotes generally the conventional drum or concrete mixer rotatably sustained between the frame members 11 comprising a carriage suitably mounted on axles 12 carrying the wheels 13 so that the drum may be moved to any preferred position.

The usual means, not shown, are also provided for rotating the drum at suitable speed for effecting the mixing operation.

Suitably pivoted at 14 to one of the frame members 11 of the carriage, is the hopper 15 carrying cable 16 which is trained over a drum connected to pulley or sheave 17, preferably journaled in any well known manner on the top of the carriage. Cable

16 is preferably wound on a cable drum (not shown) for raising the hopper to the elevated position indicated by the broken lines.

The hopper 15 is provided with a transverse plate 18 which actuates one end of the re-setting rod 19 for a purpose which will be hereinafter disclosed.

Of course, as the hopper is lowered, the cable is unwound from the winding or cable drum (not shown). The parts above described are such as are provided in

the ordinary concrete mixing apparatus now in common use, and form no part of the present invention, although they are associated

with the operation thereof.

The re-setting rod 19 extends across the carriage and is preferably slidably supported within guiding collar 20 including plate 21 which is secured to the upper frame member 22 of the carriage.

The rod 19 is provided with the bushing 23 which is fixed and held rigidly on the rod 19 by the set screw 24.

Bushing 23 and collar 20 are provided with annular plates 25 forming a bearing surface for the coiled spring 26 which loosely surrounds the rod 19 between the plates 25.

It follows, therefore, that spring 26 normally holds the rod 19 out of engagement with the control mechanism disposed within the casing 27.

The resetting rod 19 extends inside the casing 27 and is provided with a lug 28 (see Figs. 5 and 6) which is pivoted to said rod by pin 29. Said lug, however, engages shoulder 150 on bar 19, so that upon actuation of said bar the lug will move with it, but upon return movement of the bar the lug is free to swing about pin 29, as shown in dotted lines at 28' in Fig. 6. Rod 19 is guided in its travel within the casing by the depending rails 30 secured to the underface of the cover 31 of the casing 27. Disposed between the sides of casing 27 and secured thereto by rivets 32 or the like, are the pair of transverse spaced braces 33 (see Figs. 3, 5, 6 and 12) comprising the enlarged portions 34 and the reduced portions 35, (see Figs. 5 and 6). The top faces 36 of the enlarged portions 34 form guiding surfaces for the rod 19 while the top faces 37 of the reduced portions 35 are low enough to provide a slight clearance beneath the pivoted lug 28 and permit free movement thereof. Arranged within the gap formed by the spaced transverse braces 33 is the compound resetting lever 38 pivotally supported by pin 39 carried by the braces. The compound lever 38 comprises the normally elevated wing or arm 40, the inclined arm 41, and the depending unitary flat leg member 42 having a twist 43 merging into an integral transverse flat lug providing a relatively wide actuating portion 44 (see Fig. 11). Compound lever 38 is provided with the perforation 45 through which pin 39 is passed and secured to the spaced braces 33. Normally the compound lever 38 takes the position shown in Fig. 5, that is, the inclined arm 41 abuts the stop pin 46 secured to the braces 33 while the elevated arm 40 extends above the faces 37 of braces 33 forming an inclined angle therewith, said lever being held in this position by reason of the coiled spring 47, having its terminals 48 preferably secured to the flat leg 42 as at 49 and to the bracket 50 mounted on the side 50 of casing 27, as at 51.

Means have been provided for slidably supporting and guiding the control member or rack 52 (Fig. 3) on the bottom wall of casing 27. To this end, said control member is provided with a pair of perforations 53 registering with the longitudinal slot 54 in the bottom wall of casing 27. A bracket 55 (Figs. 7 and 8) mounted at one end of member 52 includes the horizontal arm having a perforation (not shown) in alignment with the perforation 53 of the control member and the longitudinal slot 54 of the casing. For slidably securing the member 52 on the bottom wall of the casing 27, the 60 stud 57 extending from the bolt head 58 is

guided within the longitudinal slot 54. Bolt head 58, of course, slides along the underface of the bottom wall of the casing, while the stud 57 extends through the perforations of the control member and of the horizontal arm 56 of bracket 55 and is clamped thereto by the nut 59. At the other end of the control member (see Figs. 3 and 8), the bracket is eliminated, and consequently the locking nut 59' secured to the upper end of stud 57 70 75 is clamped directly to the top face of the member 52, while the head 58' of said stud slidably engages the bottom face of the casing.

The control member 52 is provided with a 80 serrated edge having teeth 60, (Fig. 3). At the other side, said control member is cut away as shown at 61; so as to provide a reduced portion 63 and an enlarged portion 62, having a shoulder 61 therebetween. Said control member also has an end face 64 adapted to abut face 65 of the stop 66 when the control member is at the extreme right or starting position (see Fig. 3) at the beginning of the first revolution of the drum. The 90 stop 66 comprising a transverse block secured to the bottom face of casing 27 by the spaced bolts 67 and clamping nuts 68. Normally control member 52 is at the extreme right (as shown in Fig. 3) abutting the stop 66, due 95 to the action of the coiled spring 69 having one end 70 reflexed and secured to the standard 71 of the bracket 55 aforesaid and the other end 72 preferably secured to the bracket 73 which is rigidly mounted on the inside face 100 of the right hand end wall of casing 27.

For advancing the control member 52 periodically away from stop 66, an actuating pawl 74 having a terminal tooth 75 (Figs. 3 and 4) is adapted to enter the notches or spaces between the teeth 60 of said control member and engage said teeth so as to move the control member and the alarm actuating pin 76 thereon towards the left upon movement of said actuating pawl in that direction. The actuating pawl 74 is pivotally connected to the end of a slideable offset plate 77 having longitudinal guide slot 78 through which extend headed studs 79 secured to bolts 80 passing through the bottom wall of the housing 110 (see Figs. 3, 5 and 8). The stud heads 81 hold plate 77 down onto the bottom wall of the housing, while permitting the same to slide thereon. The other end 82 of slideable plate 77 is offset by the inclined intermediate 120 portion 83, and rests upon the top face of a lever 84. Said lever is suitably fulcrumed by pin 85, having a head 87 (see Fig. 5) and extending through said lever, through a spacing ring or boss 88, and through the bottom 125 of the casing 27, and provided with a nut 86.

The actuating pawl 74, the lever 84, the offset portion 82 and the plate 89 (Figs. 3 and 8) are pivotally connected by stud 90 preferably having its lower head 91 countersunk 130

in pawl 74 and these parts are held together by the clamping nut 92. These parts therefore move bodily as lever 84 is actuated by pin 93 (see Figs. 2 and 3) mounted on the revolving concrete mixing drum 10, moving in the direction of the arrow in Fig. 3. The length of guide slot 78 determines the length of each movement of the actuating pawl, as hereinafter described.

10. Normally the coiled spring 94 which is secured to plate 89, as at 95 and to the fixed bracket 96 mounted on the right end wall of casing 27, as at 97, holds lever 84 in the position shown in Fig. 3, that is, in the path of pin 93, so as to be actuated by the latter upon each revolution of the drum and cause consequent movement of pawl 74 and slideable bar 77 to the left against the action of said spring.
20. As the pawl 74 moves to the left, tooth 75 bears against one of the teeth 60 of the control member 52 so that the latter in turn is likewise moved to the left, a predetermined distance.
25. The pawl 74 is provided with an upstanding pin 95 forming an abutment for the free end of leaf spring 96 which is secured to the intermediate portion 83 of the offset plate 77 in any suitable manner. Normally the compression of spring 96, holds tooth 75 of pawl 74 in engagement with the teeth 60 of the control member, but permits the end of said pawl to slide back over said teeth during the backward movement of the pawl.
35. For locking the control member 52 in its advanced position upon each revolution of the drum, a holding pawl 97 is provided having the terminal tooth 98 normally held between teeth 60 by the action of leaf spring 98 (shown in Fig. 3 but removed in Fig. 8) having its free end abutting pin 99 on the pawl. The other end of spring 98 is coiled or reflexed about pin 100, preferably secured to casing 27 and is supported by the supplemental fixed pin 101 likewise held to the casing in any preferred manner. Holding pawl 97 is preferably pivoted to the lower wall of casing 27 by the bolt 102 having its shank extending through the pawl and the casing 27 and being clamped by the adjustable nut 103.
40. Referring to Fig. 4, it will be apparent that as the control member 52 is advanced to the left by tooth 75 of the actuating pawl 74, tooth 98 of the holding pawl 97 will ride over a tooth of the rack 52 originally locked by said holding pawl, prior to the operation of the actuating pawl 74. As disclosed, the length of slot 78 is such as to provide for movement of control member 52 through a distance sufficient to cause passage of one tooth beneath the holding pawl 97 and permit said pawl to enter between that tooth and the next, so that, upon each revolution of the drum 10, the control member is advanced a distance equal to the pitch of the teeth thereon; but it is within

the scope of the invention, to change the length of said slot, or the position of said stud, and to also vary the leverage of lever 84 if desired, so that the control member 52 may be moved a distance corresponding to the width of any number of teeth, or a distance corresponding to any desired fraction of its total movement, upon each revolution of the mixing drum.

Mounted on lever 84 at the outer end thereof is the yieldable finger 104 which is pivotally secured thereto by the rivet or the like 105. Said finger 104 (as shown particularly in Figs. 3 and 9) is provided with an arcuate or inclined end face 106 and includes the depending side abutment 107 forming a shoulder engaging the side of lever 84. The spring 108 (Figs. 3 and 5) which is secured to abutment 107 and to a bracket 109 fixed to lever 84, normally holds finger 104 in alignment with lever 84, with abutment 107 normally in contact with the outer face of the lever.

Spring 108 is relatively strong, so that as long as the pawl 74 is free to move, engagement of pin 93 with finger 104 will cause said finger and lever 84 to move bodily, advancing the control member as above described. However, when said pawl is stopped by engagement of the end of slot 78 with stud 79 as above described, spring 108 will yield sufficiently to permit finger 104 to swing about its pivot 105 until pin 93 passes over and releases said finger. Spring 108 then returns said finger to normal position, while spring 94 returns lever 84 and pawl 74 to their initial position.

The discharge chute 118, shown in lowered or discharging position in Fig. 1, and in raised or non-discharging position in Fig. 2, is secured by lugs 117 to a shaft 115 rotatably supported on bearing brackets 116 secured to the frame members 11, and is provided with a hand-lever 119 for operation thereof to either of the above positions. Said discharge chute is preferably so mounted that it will tend to remain in either discharging or non-discharging position when moved to such position, so that the actual movement thereof to either position must be effected by the operator. By means of our control device, however, said chute is prevented from being lowered to discharging position during the mixing operation. For this purpose, a rod 112, which may have an intermediate offset 112', is connected at its lower end by a short lever arm 114 to shaft 115 and is pivotally connected at its upper end, as at 113, to a locking bar 111, extending vertically upward into the casing 27 and slidably guided within a guide housing formed by wall portions 122, 123, 124 and 125 of bracket 126 secured to the side wall of the casing as by rivets 127. Said locking bar is provided with a latch member or dog 110, resiliently mounted thereon by leaf spring 128 fastened to said rod by screw 129. Said

75

80

85

90

100

105

110

115

120

125

130

spring tends to hold latch member 110 forwardly into position above the enlarged portion 62 of control member 52, so that as long as any part of said enlarged portion is beneath said latch member, locking bar 111 and hence discharge chute 118 are locked in raised position. The bottom wall of casing 27 is provided with an opening 121 through which locking bar 111 passes, said opening being sufficiently large to provide a space 121' at one side of the locking bar for passage of latch member 110 on lowering of said locking bar, and a space 121'' at the other side of said locking bar to permit outward movement of said latch member against the action of leaf spring 128 upon upward movement of said locking bar. Such outward movement of the latch member is caused by the inclined face 130 thereof engaging the face of the enlarged portion 62 of control member 52 when the locking bar is raised under certain conditions, as hereinafter described. The outline of opening 121 is shown in dotted lines in Fig. 12.

For notifying the operator that the drum has made a predetermined number of revolutions and that the discharge chute is free to be lowered, pin 76 on control member 52 (see Figs. 3 and 7) is provided, adapted to engage lever 131 forcing the latter to move lug 132 against which it bears, and hence to move the bell-crank lever 133 comprising arm 134 to which is secured one end of coiled spring 135, the other end of said spring being secured to bracket 136 rigidly carried by casing 27. The flat spring arm 137 also extends from the bell-crank lever 133 and is provided with a clapper 137'. Lever 131 and bell-crank lever 133 are pivotally supported on pin 138 extending upwardly from the bottom wall of casing 27 and preferably secured thereto by the locking bolt 139. For limiting the swing of the spring arm 137 upon release thereof as hereinafter described, a stop pin 140 is provided projecting inwardly from casing 27 and is secured thereto at 141 in any well known manner. Normally lever 131 bears against the lug 132 due to the force of the leaf spring 142 which connects said lever with the arm 134, while arm 137 is held against stop pin 140 by spring 135.

Thus, it follows, that as the pin 76 strikes lever 131, the bell-crank lever 133 is actuated in a counter-clockwise direction (in Fig. 3), and accordingly retracts clapper arm 137 against the action of spring 135. As the pin 76 passes over and beyond the tip of lever 131, spring 135 compresses, swinging arm 134 and spring arm 137 in the reverse direction so that altho arm 137 is arrested by stop 140, the resiliency of said arm causes the clapper 137' to swing through opening 143 in the casing and to strike the gong 144 carried by the casing, and thereby sound an audible alarm, indicating that the discharge chute should be lowered. In the return of

pin 76 to the right it will ride over the inclined face 145 of lever 131 and the latter will yield or move against the leaf spring 142, to permit pin 76 to clear the tip of said lever.

In the operation of the apparatus, the hopper 14 is first charged with proper ingredients and raised by means of cable 16. As the hopper rises toward the vertical, the ingredients are fed and discharged into the mixing drum. Further movement of the hopper causes the transverse plate 18 to bear against the outer end of re-setting rod 19, moving the latter inwardly and causing lug 28 to depress arm 40 of the compound lever 38 to swing the latter down to the position shown in full lines in Fig. 6, against the action of spring 47, so that lug portion 44 of the compound lever 38 strikes against pin 99 of the holding pawl 97 and pin 95 of the actuating pawl 74. Accordingly, pawls 97 and 74, are moved out of engagement with the teeth 60 of the control member 52, as shown in full lines in Fig. 6, permitting said control member to slide automatically to the right by the action of spring 69, until end face 64 bears against the flat face 65 of stop 66. The function of the re-setting rod 19, therefore, is to actuate the compound lever, to release the holding and actuating pawls from the control member and allow the latter to be re-set against the stop prior to the first revolution of the mixing drum following charging thereof.

The pivoted lug 28 rides over the full length of the arm 40 of compound lever 38, and as soon as it passes beyond the end thereof, said lever is returned by spring 47 to the position shown in dotted lines in Fig. 6. As the charging hopper is then lowered to be re-loaded, spring 26 returns re-setting rod to normal position, and in this movement the lug 28 swings upwardly about pivot 29, as also shown in dotted lines, so as to ride over arm 40 without depressing the same.

If the delivery chute was already in raised or non-discharging position, as shown in Fig. 2 and in dotted lines at 118' in Fig. 1, prior to re-setting of the control mechanism, the enlarged portion 62 of the control member will be brought beneath latch member 110 to hold the same in this position. In ordinary operation, the delivery chute should be moved to this raised or non-discharging position either before or immediately following the re-setting operation. In the latter case, latch member 110 of the locking bar will be pressed back against the action of spring 128 and then snap forward into locking position of engagement with the upper face of said enlarged portion of the control member. It will be noted, however, that, if the operator should neglect to raise the delivery chute before or immediately following charging of the mixing drum, the rotation thereof will

70

75

80

85

90

105

110

115

120

125

130

nevertheless begin to operate the control mechanism, and the delivery chute may be raised and locked in the same manner, at any time thereafter. Therefore, in any case, the control mechanism operates to cause the mixing drum to make the required number of revolutions following charging of the unmixed ingredients therein, regardless of the time at which the delivery chute is raised to non-discharging position. This not only insures adequate mixing of every batch of concrete, but prevents any loss of time due to the operator failing to immediately raise the delivery chute.

The rotation of the drum serves to mix the ingredients charged therein and it follows, that upon each revolution made, pin 93 (see Figs. 2 and 3) will strike and pass the tripping finger 104, consequently moving the actuating lever 84 to the right in Fig. 3, so that tooth 75 of the actuating pawl 74 will move the control member to the left or away from the stop 66. The holding pawl 97 prevents the retraction of the control member as heretofore set forth. The same operation continues at each revolution until the cut away portion 61 of the control member comes under the latch member 110 of the chute-locking bar 111. The control member has at this time advanced to a position furthest away from the stop 66 and at this position also pin 76 on said control member actuates lever 131 so that clapper 137 swings through aperture 143 to strike the gong 144 sounding an audible alarm, indicating that the ingredients in the drum have been mixed and the mass is ready to be discharged from the drum, and that the locking means for the chute has been released by the control mechanism. The control member is now at its extreme position, for the reason that there are no more teeth on the same for the actuating pawl to engage. Until the charging hopper again resets the control member, the pawl 74 is still actuated at each revolution of the mixing drum, but the control member cannot advance further. The operator now lowers the delivery chute 118 by actuating handle 119 which causes latch member 110 on locking bar 111 to pass through the cut away portion of the control member and through opening 121 to a position below casing 27 as shown in Fig. 6. After the supply of mixed concrete in the drum has been discharged through chute 118 or while it is being so discharged, the charging hopper is again raised to introduce a fresh batch of materials, and the timing mechanism is re-set as before.

Referring to the modification disclosed in Figs. 14 to 19 inclusive, there is illustrated a control device cooperating with a concrete drum mixer whereby the ingredients fed into the drum are permitted to commingle or mix a predetermined number of revolutions, the control device comprising essentially a slid-

able and rotatable pinion adapted to actuate a slideable control member, by engagement with a rack thereon, from the starting or setting position at the beginning of the first revolution of the drum until the control member has reached the limit of its travel, during which time the drum has made a predetermined number of revolutions; and at the limit of the travel or stroke of the control member, the latter actuates automatically an audible alarm, notifying the operator, that the chute has been unlocked by the control device to permit the mixed wet concrete from the drum to be delivered or discharged by manually lowering the delivery chute.

The apparatus illustrated consists as before of the mixing drum 10 (see Fig. 14) suitably mounted on wheels 11 and provided with rotating means and with means such as above described for charging the ingredients into the drum and for delivering the mixed concrete therefrom. Drum 10 is provided with brackets 212 fixed on its circumferential surface, adapted to actuate radially disposed arms 214 of spider 215 which is rigidly secured to the timing shaft 216 suitably journaled in sides 217 and 218 of casing 219 containing the control mechanism.

Longitudinally disposed in spaced relation and preferably rigidly secured to the bottom wall 221 of casing 219 by the outwardly extending flanges 220 by means of the set screws 222 or the like, is the pair of supporting bars 223 having inwardly disposed flanges 224 forming rails for the control member 225 including on its upper face a plurality of teeth 226 comprising a rack, generally denoted by 227. The rack, of course, is an integral part of the control member 225, and the latter is guided in its travel along the rails by inwardly disposed flanges 228 extending from the side plates 229 which are preferably secured to the corresponding bars 223, in any well known manner.

The control member 225 is provided with a longitudinal groove 230 adapted to lock the depending lug 231 of dog or latch 232 having the inclined upper face 233 and a flat outer face 234 to which is connected flat leaf spring 235 secured to the reciprocating chute-locking bar 236. Bar 236 is, of course, connected to, and responsive to the raising and lowering of, the discharge chute (not shown) in the same manner as the chute locking bar in the modification above described, and is adapted to slide within the opening 238 in bottom wall 219 of the casing. The object of this construction is to permit the discharge chute to be raised at any time even though the control mechanism has been started. The supporting and guiding members 220, 223, 224, 228 and 229 at this side of the control member are also cut away at the position of the locking bar, as shown in Figs. 15 and 18, so as not to interfere with

the movement of said locking bar. Thus it will be seen that as the locking bar 236 is elevated by raising the discharge chute (assuming the control mechanism has been reset), the latch member 232 will ride upwardly and against the control member 225, consequently bending or reflexing the leaf spring 235 out of alignment until the lug 231 comes over the adjacent top face of said control member, whereupon the resiliency of leaf spring 235 will swing the lug 231 of latch 232 in registration with groove 230 of the slide bar 225, consequently locking the chute until said control member has reached the limit of its stroke, as will be more fully hereinafter set forth.

The control member 225 is provided at one end (see Fig. 17) with a bracket 239 suitably fixed thereon having the depending arm 240 to which is secured one terminal 241 of the coiled spring 242 disposed under the control member, while the other terminal 243 of the spring 242 is secured to an eye 244 preferably mounted on an end wall of the casing. Coiled spring 242 serves to return the control member to the starting position, namely, the position shown in Fig. 17, against a stop member 299 at the extreme left of the casing. It will be noted that the control member 225 includes the cut away portion or elongated notch 245 (Fig. 15) which comes under the latch 232 when said control member has been moved to the right a distance corresponding to a predetermined number of revolutions made by the drum.

Suitably mounted within the casing 219 is the transverse rod 246 which is mounted to slide through the longitudinal sides 217 and 218, in bushings 247 and 248 respectively. Preferably rigidly and adjustably secured to rod 246 is the collar 249, as by means of set screw 250. The collar 249 is provided with a tapering extension arm 251 whose outer end 252 is adapted to actuate the pinion and retaining pawl as hereinafter described.

Disposed between the transverse rod 246 and the shaft 216 is the guiding rail 253 comprising an elongated bar having horizontal offset top faces 254 and 255 connected by the inclined shoulder 256 (Figs. 15 and 16). The rail 253 is secured to the wall 218 of casing 219 by the flange 257, by means of the screw 258. Normally arm 251 rests upon the horizontal face 254, that is, before slideable rod 246 has been actuated by the hopper (not shown). It will be understood that rod 246 performs the function of re-setting the control mechanism, in the same manner as the rod 19 of the apparatus first described, and that it may be similarly mounted above the mixing drum in position to be engaged and forced inwardly upon raising of the charging hopper, and also that a spring, corresponding to the spring 26 of the other modi-

fication, may be provided for returning said rod to normal or retracted position.

The shaft is provided with a longitudinal key-way 259 (see Fig. 19) in which key 260 is held, so that the pinion 261 is slideable on the key but rotatable with shaft 216. Said pinion engages the teeth of rack 227. Straddling pinion 261 is the cage 262 comprising an open frame having side members 263 loosely surrounding shaft 216 and integrally connected by the cross strap 264 and including tapered downward and outward extensions connecting pawl member 266 engaging rack 227 so as to form a retaining element for the control member.

For normally maintaining the pawl 266 in locking engagement with the rack, a coiled spring 267 is provided surrounding shaft 216, and is secured to one of the side members 263 at 268 and to the side wall 218 of the timing casing at 269. Said spring not only serves to normally hold the pinion 261 and pawl 266 away from side wall 18 and in alignment with the rack, but also exerts a rotational force on the cage 262 tending to hold said pawl downwardly into engagement between the teeth of said rack. The longitudinal movement of said pinion and pawl, under the action of said spring, is limited by engagement of key 260 with the end of key-way 259. Cage 262 is also provided with a lateral extension arm 270 which is at a level slightly below the face 255 of rail 253, for a purpose hereinafter explained.

When the control member 225 has been moved the complete length of its stroke corresponding to a predetermined number of revolutions of the drum, that is, when it is at its extreme right hand position, the cut away portion 245 thereof is brought into position beneath latch 232, so as to unlock the chute. At the same time, a pin 271 on the control member comes in contact with tip 272 of lever or dog 273 which abuts lug 275 extending from lever 276. Dog 273 and lever 276 are both pivotally mounted on pin 277. Extending from the lever 276 is a flat spring arm 278 to which is secured at its free end clapper 279 adapted to pass through opening 280 of the casing and strike the gong 281 secured to the casing to sound an audible alarm. It will be noted that dog 273 is provided with the arcuate face 282, to permit pin 271 to pass by upon the return of the control member to the starting position. Lug 275 abuts the leaf spring 283 which is secured to the casing at 284. Secured to the spring arm 278 is the leaf spring 285 which is adapted to engage pin 286 extending from dog 273, so as to normally hold said dog against lug 275. Leaf spring 283 normally holds the spring arm 278 in engagement with stop pin 287.

The operation of this form of control member is as follows:—Assuming first, that the

control member 225 is at the extreme right and that the hopper (not shown) has been charged with the proper materials to be delivered into the drum. The re-setting of the mechanism is accomplished upon raising the hopper to abut and move or slide rod 246 in the bearings 247 and 248. Collar 249 and arm 251 are thus moved to the right in Fig. 16, so that the outer end 252 of said arm abuts against side member 263 of the cage 262, moving the latter and the pinion 261 out of engagement with the rack 227 (see Fig. 16). Consequently the control member at once slides back on rails 224 to the starting or setting position, as a result of the contraction of the coiled spring 242. However, as the hopper continues to be elevated, portion 252 of arm 251 rides along the inclined shoulder 256 and onto the horizontal face 255 of the rail 253, to the position indicated by the dotted lines at 252' in Fig. 16, and as the portion 252 rides up on the inclined shoulder 256 it passes over the rounded upper corner 263' of side member 263 of cage 262. The latter is then returned by spring 267, to bring pawl 266 and the pinion 261 back into position of engagement with the rack 227, due to the action of spring 267.

The delivery chute may, as before, be raised to non-discharging position at this time, or at any time thereafter, spring 235 yielding as above described to permit latch member 232 to pass the side of control member 225 and into locking position.

The drum is rotating, and upon the first revolution after the control member has been re-set, bracket 212 will strike an arm 214 of spider 215 thereby actuating shaft 216 which in turn will rotate pinion 261 to cause the control member to move to the right a distance corresponding to the angular distance between arms 214. As the pinion advances the control member, pawl 266 engages the rack to lock the same in advanced position, engaging between the teeth 226 in advance of the pinion and thereby preventing retraction of the control member. The same cycle continues until latch 232 registers with notch 245, after which the delivery chute may be lowered to discharging position. At the same time, the gong 281 is struck, due to engagement of pin 271 with dog 273. Said pin first moves said dog forward, which engages lug 275 to swing lever 276 and spring arm 278 in a counterclockwise direction (in Fig. 15), but as the pin passes over the tip of dog 273, said lever returns and strikes stop 287, while spring arm 278 continues its movement, causing clapper 279 to strike gong 281.

When the audible signal has struck, the chute is lowered, consequently moving the locking bar 236 and latch 232 through opening 238 in the casing. As the drum revolves, the charging hopper of course is be-

ing supplied with the proper materials so that the drum can be immediately charged, after the chute has discharged the contents from the drum. In this way, considerable labor and time is saved, in addition to providing concrete having desirable qualities, namely, proper strength, consistency and uniformity.

It is evident that, in either of the forms of the invention above described, the duration of the mixing period may readily be varied. For example, the stop plate 66 of the first form, or stop plate 299 of the second form, may be made in a number of different lengths, so that by interchanging said plates, the length of stroke of the control member may be varied, so as to cause the mixing drum to make any desired number of revolutions before unlocking of the discharge chute by said control member.

From the foregoing description, considered in connection with the accompanying drawings, it is believed that the several novel structural features of our present improvement as well as the advantages thereof will be readily appreciated and it will be obvious to those skilled in the art, after an understanding of our invention, that other changes and modifications may be made without departing from spirit and scope of our invention and it is proposed in the appended claims, to cover such changes and modifications as are within the scope of the invention.

We claim:

1. In combination with a drum for mixing concrete and with a charging hopper and a discharge chute therefor, a control mechanism associated therewith comprising a casing having a control member slidably disposed therein, a stop at one end of said casing, means tending to hold said control member against said stop, a holding member carried by the casing normally locking said control member against movement toward said stop, an actuating member disposed within the casing and responsive to the rotation of said drum for moving said control member away from said stop, and means responsive to the raising of said hopper for releasing both said holding member and said actuating member, to permit return of said control member against said stop.

2. In combination with a drum for mixing concrete and with a charging hopper and a discharge chute therefor, a control mechanism associated therewith comprising a casing having a control member slidably disposed therein, a stop at one end of said casing, means tending to move said control member against said stop, a holding member normally locking said control member against movement toward said stop, an actuating member mounted within the casing and responsive to the rotation of said

drum for moving said control member a predetermined distance away from said stop upon each revolution of said drum, and means responsive to the raising of said hopper for releasing both said holding member and said actuating member to permit return of said control member against said stop.

3. In combination with a mixing drum and with a charging hopper and a discharge chute therefor, a control mechanism associated therewith comprising a casing having a control member slidably disposed therein, a stop at one end of the casing, means tending to move said control member toward and against said stop, actuating means operable upon each revolution of the drum for moving said control member a predetermined distance away from said stop, and locking means connected to said chute and adapted to engage said control mechanism to lock the chute in inoperative position, said control member being provided with a cut away portion adapted to register with said locking means and release the same, for unlocking said discharge chute, after a predetermined number of operations of said control member by said actuating means.

4. In combination with a mixing drum and with a charging hopper and a discharge chute therefor, a control mechanism associated therewith comprising a casing and a control member slidably mounted therein, a stop carried by the casing, means tending to move said control member toward and against said stop, holding means extending from said chute and adapted to be locked by said control member, means for advancing said control member away from said stop upon each revolution of the drum, and means for releasing said holding means from the control member after the drum has made a predetermined number of revolutions.

5. In combination with a mixing drum and with a charging hopper and a discharge chute therefor, a control device associated therewith adapted to be set by said hopper and comprising a casing including a stop and a slidably disposed control member abutting said stop, a locking bar extending from said chute and having a resilient plate secured thereto carrying a latch member having an inclined face extending beyond the bar and adapted to move in alignment with the bar in raising the chute after the timing device has been set, said resilient plate being adapted to yield and permit said latch member to ride over said control member and to be locked thereby.

6. In combination with a rotatable drum for mixing concrete and with a charging hopper and a discharge chute therefor, a control mechanism associated therewith comprising stop means, a control member mounted to slide between a position against

said stop and a releasing position removed from said stop by a definite distance, means tending to move said control member toward and against said stop means, a holding member normally engaging said control member to hold the same against movement toward said stop means, an actuating member normally engaging said control member and operable to move the same from position against said stop means toward said releasing position, means operable upon rotation of said mixing drum to cause said actuating member to move said control member a definite portion of the distance between said positions upon each rotation of said drum, locking means connected to said discharge chute and movable, upon movement of said discharge chute to non-discharging position, to position to be engaged and locked by said control member when the latter is in any position other than said releasing position, said control member being adapted, upon reaching said releasing position, to release said locking means and permit movement of said discharge chute to discharging position.

7. An apparatus as set forth in claim 6, and comprising in addition, means responsive to movement of said charging hopper to charging position, for moving both said holding member and said actuating member out of engagement with said control member, so as to permit return of said control member against said stop.

In testimony whereof we have hereunto subscribed our names this 14th day of February, 1929.

OLIVER JOHNSON.
RAYMOND G. SANDERS.
